WINDOW

Clyde W. Kelly, Detroit, Mich., assignor to Detroit Steel Products Company, Detroit, Mich., a corporation of Michigan

Application October 7, 1935, Serial No. 43,944

11 Claims. (Cl. 189—37)

The invention relates to windows and refers more particularly to windows of the awning type.

Heretofore, awning type windows have been constructed comprising a frame, a plurality of superimposed swinging ventilators and bars connecting the ventilators so that they would swing in unison. To provide for fully closing each of the ventilators so that it would closely engage the frame, the bars connecting the adjacent ventilators have been adjustably connected to each other. This construction requires considerable shop labor and expense in securing the desired adjustment of the ventilators and often times requires considerable labor and expense after the window has been installed, inasmuch as the adjustments must be made when the ventilators are in open position.

The invention has for one of its objects to improve upon this construction and has for another of its objects to provide an adjustment which is readily accessible. The invention has for further objects the novel arrangement and combinations of parts, as more fully hereinafter set forth.

In the drawings:

Figure 1 is a perspective view of a window disclosing an embodiment of my invention;

Figure 2 is an elevation, broken away, of a portion of Figure 1;

Figure 3 is a vertical section through Figure 1;

Figure 4 is a cross section on the line 4—4 of Figure 2;

Figure 5 is an elevation, with the cover broken away, of one of the adjustable connections shown in Figure 3;

Figure 6 is a plan view thereof;

Figures 7 and 8 are cross sections on the lines 7—7 and 8—8 respectively, of Figure 5;

Figure 9 is an enlarged cross sectional view of a portion of Figure 2.

The window illustrated in the drawings is of the awning type and comprises the frame 1 and the ventilators or sashes 2, 3 and 4 mounted to swing outwardly to open position. Each ventilator has pivotally mounted at its upper end of the

pair of horizontally aligned channel-shaped shoes 5, which extend laterally and slidably engage the channels 6 of the jambs 7 of the frame 1. Each ventilator is also connected to the frame 1 by the pair of horizontally aligned fulcrum side arms 8, there being one at each side of each ventilator intermediate its side rails and the adjacent jambs.

The upper ends of these side arms are pivotally connected with the side rails of the ventilators at 9 intermediate the top and bottom rails of the ventilators and the lower ends of these side arms

are pivotally connected to the jambs 7. The lower ends of the side arms 8 of the lower ventilator 4 are pivotally connected to the jambs in the usual manner, while the lower ends of the side arms 8 of the upper and intermediate ventilators 2 and 3, respectively, are pivotally connected to the extension plates 9, which are fixedly secured to the jambs as by being welded thereto and which extend inwardly. The side arms of these ventilators 2 and 3 extend through the openings 10 or slots 10 formed in the jambs. With this mounting, the upper end of each ventilator is guided by the jambs of the frame and each ventilator upon movement of its upper end will swing by reason of its fulcrum side arms. 15

For operatively connecting the ventilators to swing in unison, I have provided a bar mechanism comprising the bars 11, 12 and 13 which bar mechanism is arranged in the channel of each jamb 7 and intermediate the jamb and the side rails of the ventilators when closed. The bar 11 is embraced by the adjacent shoe 5 of the upper ventilator 2 and is fixedly secured below this shoe to the bar 12 by means of the screws 14. The bar 12 is embraced by the adjacent shoe 5 of the intermediate ventilator 3 and is fixedly secured below this shoe to the bar 13 by means of the screws 15. The bar 13 is embraced by the adjacent shoe 5 of the lower ventilator 4. The bars 11, 12 and 13 are provided with the notches 11', 12' and 13' respectively, for receiving the bases or webs of their respective shoes. The bar 11 is maintained in engagement with its shoe 5 by reason of the limited lateral clearance between the lower end of the bar 12 and the web of the channel 8. The bar 12 is maintained in engagement with its respective shoe by reason of the limited lateral clearance between the upper end of the bar 13 and the web of the channel 8. As shown in the present instance, the bar 13 is maintained in engagement with its shoe by reason of the resiliency of this bar 13 which constantly urges the lower end of this bar toward the shoe. By reason of the bar mechanisms, the ventilators 2 and 3 above the ventilator 4 will swing in unison with the ventilator 4 since the bar mechanisms are reciprocated by swinging of the latter ventilator. 45

To secure close engagement of each of the ventilators with the frame, or in other words, full closing of each of the ventilators and thereby effective sealing of the joints between each of the ventilators and the frame, I have made the ventilator connections between the fulcrum side arms 8 of the ventilators 2 and 3 and the extension 55

plates 9 individually adjustable. In detail, and as more particularly shown in Figures 5, 6, 7 and 8, each of these side arms is journaled at its lower end upon the horizontal screw 16 which is threaded into the block 17. This block is formed with the internally threaded vertical bore 18 laterally outwardly beyond the screw 16 and this bar is engaged by the machine screw 19 having the head 20 rotatably engaging the lower horizontal flange 21 formed upon the extension plate 9. The upper end of the machine screw is journaled in the bushing 22 which has the head 23 rotatably mounted in the upper horizontal flange 24 of the extension plate. The machine screw is vertically positioned by suitable means such as the pin 25 which extends transversely through the bushing and the upper end of the machine screw, or by welding the machine screw to the bushing as at 25'. The head 20 is preferably provided with the slot 26 for engagement by a screw driver whereby the machine screw may be rotated to thereby raise or lower the block 17 and with it the pivot for the lower end of the side arm. 27 is a sheet metal cover which may be readily slipped over the extension plate and the associated mechanism and secured in place by suitable means, such as the screws 28, which may be threaded into the horizontal flanges of the extension plate.

From the above description, it will be readily seen that I have provided a window in which one or more ventilators are swung in unison with another ventilator and in which adjustment may be readily made for the one or more ventilators to enable full closing of the same. It will also be seen that each adjustable device is readily accessible by simply removing its cover and, furthermore, that it may be adjusted when the ventilators are in closed position so that considerable labor and expense may be avoided.

What I claim as my invention is:

1. A window, comprising a frame, a plurality of swinging ventilators, means connecting said ventilators whereby the same swing in unison, fulcrum means for said ventilators pivotally connecting said ventilators and frame, one of the pivotal connections between said fulcrum means and said frame and one of said ventilators being adjustable to provide for fully closing said last mentioned ventilator upon full closing of the other of said ventilators, and means for adjusting said last mentioned pivotal connection when said last mentioned ventilator is closed.

2. A window, comprising a frame, a plurality of swinging ventilators, and means connecting said ventilators whereby the same swing in unison, of side arms pivotally connected to one of said ventilators and also pivotally connected to said frame, one of the pivotal connections of each side arm being adjustable when the ventilator connected thereto is in closed position whereby said ventilators may occupy fully closed positions.

3. A window, comprising a frame, a plurality of swinging ventilators, bar means connecting said ventilators whereby the same swing in unison, and side arms pivotally connected to said frame, and also pivotally connected to said frame, one of the pivotal connections being adjustable when the associated ventilator is in closed position whereby said ventilators may occupy fully closed positions.

4. A window, comprising a frame, a swinging ventilator, means for guiding one end of said ventilator upon said frame, and fulcrum means for said ventilator pivotally connecting said ven-

tilator and frame, said guiding means having a predetermined limit of travel in a direction to close said ventilator and one of the pivotal connections being adjustable when said ventilator is closed whereby said ventilator may be fully closed. 5

5. A window, comprising a frame, a swinging ventilator having a portion movably connected to said frame, fulcrum bar means pivotally connected at one end to another portion of said ventilator, an adjustable pivot for the other end of said fulcrum bar means, and means upon said frame adjustable when said ventilator is in closed position for varying the position of said adjustable pivot relative to said frame.

6. A window, comprising a frame, a swinging 15 ventilator having one portion movably connected to said frame, fulcrum side arms pivotally connected to another portion of said ventilator, rotatably adjustable screws mounted upon said frame and held from longitudinal movement relative thereto, and members threaded upon said screws and pivotally connected to said fulcrum side arms.

7. A window, comprising a frame, a swinging 25 ventilator, means for guiding one end of said ventilator upon said frame, side arms pivotally connected at one end to said ventilator, plates upon said frame, screws journaled in said plates and held from longitudinal movement relative thereto and blocks threaded upon said screws and pivotally connected to the opposite ends of said side arms.

8. A window, comprising a frame, a swinging 35 ventilator, means for guiding one end of said ventilator upon said frame, fulcrum side arms 35 pivotally connected at one end to said ventilator, extension plates fixedly secured to said frame and extending inwardly therefrom, each of said plates having spaced apart substantially parallel flanges, a screw extending substantially parallel 40 to said frame and rotatably carried by said flanges of each extension plate, a block threaded upon each screw, and a pivot for the opposite end of each arm carried by each block.

9. A window, comprising a frame, a swinging 45 ventilator, fulcrum means for said ventilator pivotally connecting said ventilator and frame, said fulcrum means comprising a side arm extending between adjacent bars of said frame and ventilator when the latter is closed and having an end portion extending transversely of and beyond 50 said frame bar, and an adjustable support upon and beyond said frame bar for said end portion.

10. A window comprising a frame having a jamb, a swinging ventilator, means for guiding one end of said ventilator upon said frame, fulcrum means for said ventilator comprising an arm pivotally connected at one end to said ventilator, and an adjustable pivotal connection between the other end of said arm and said jamb, 60 said adjustable pivotal connection being offset relative to said jamb and being adjustable when said ventilator is in closed position.

11. A window comprising a frame having a jamb, a swinging ventilator, means for guiding one end of said ventilator upon said frame, said means comprising a member pivotally connected to said ventilator, fulcrum means for said ventilator comprising an arm pivotally connected to said ventilator and jamb, one of said pivotal connections being adjustable and being offset relative to said jamb and accessible when said ventilator is in closed position. 70
